UNITED STATES PATENT OFFICE.

JAMES J. OGILVIE, OF STAUNTON, VIRGINIA.

FOLDING FENCE-PANEL.

SPECIFICATION forming part of Letters Patent No. 319,995, dated June 16, 1885.

Application filed October 12, 1883. (No model.)

To all whom it may concern:

Be it known that I, JAMES J. OGILVIE, a citizen of the United States, residing at Staunton, in the county of Augusta and State of Virginia, have invented certain new and useful Improvements in Folding Fence-Panels; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in fences; and it consists in a fence-panel capable of being folded for transportation, so that the folded panel shall occupy a space equal only to the width of its single rail, and in the method 20 of connecting two or more of the same, as will be hereinafter fully shown and described in the drawings and specification.

The objects of my invention are, first, to construct a fence-panel which shall be formed 25 of a single rail and a series of wires or wooden slats, which shall be extended between and pivoted to two uprights, and so arranged that it can be folded for transportation so as to occupy only the space of the rail or cross-piece; 30 and, secondly, conveniently to connect two panels, as is hereinafter more particularly and specifically pointed out in the claims. These objects I attain in the manner illustrated in the drawings, in which—

35 Figure 1 shows a panel of my fence mounted on its sills, adjusted for level ground, and having attached the rail of a second panel. Fig. 2 is a view of a panel folded for transportation. Fig. 3 is a sectional view of the rail 40 ends and brace, showing the method of connecting the panels when they are in a continuous line. Fig. 4 is a view of the sill I. Fig. 5 shows the means for turning a corner. Fig. 6 is an end or foot view of the upright B. Fig. 45 7 is a view, partly in section, of the upright, the rail ends, and the brace, and the means for adjusting the lower ends of the brace and the upright upon the sill.

50 A is the rail, and B and B' are the two uprights, which are pivoted to the rail by the pivots a.

C C C are a series of wires or slats extend-

ing from the upright B to B' and attached to the headed projection b in the respective uprights. The pairs of projections b are not directly over each other, but each pair is placed a little to the right of the pair below, which 55 enables the panel to be folded.

Where wire is used, the ends of the wires are looped around the projections b and then 60 wound around the body of the wires. With wooden slats the projections will pass or be driven through holes in the ends of the slats. In either case the wire or slat will turn freely 65 on the projections b when the panel is to be folded. The panel is prevented from folding together at other times by a pin which passes through an opening, D, in the upright B' and the rail A and holds them together.

The bottom of the upright B is slightly beveled and provided with a recess, E, to receive 70 a pin, F, in the sill.

The ends of the rails A are dovetailed or rabbeted to make connection with the next panels, and notched to receive a wire loop, p, 75 which is attached to the under side of rail A and passes over the top thereof to receive the upper end of the brace G, which supports the panel, and serves also, with the wire loop p, to connect each two panels.

The sill I has at its center a notch, i, to receive the beveled end of the upright B, and in this notch is a pin or projection, F, which enters the opening E in the foot of the upright. 85

A metallic plate, j, at the side of the sill receives through an opening therein a pin, k, which enters upright B and connects the same with the sill.

Near the rear end of the sill are three or 90 more holes, l l' l'', one above the other, and on the opposite side the end of the sill is beveled and has two or more holes, m m', to receive the pin n, by which the lower end of the brace 95 G is attached to the sill. This brace G has a shoulder, g, near its top which rests on the top of rail A, and an opening, o, at its foot, through which the pin n passes to enter one of the holes l or m, according as the slope of the panel is changed. The upright B' is designed 100 to rest on a plain sill, I', without either connection or brace.

For the purpose of connecting two panels in a continuous line the end of the rail A is rab-

beted on its front side to half its thickness, to receive the end of the corresponding rail, A', of the next panel, which has a like rabbet on its rear side, the two ends when meeting being together only the thickness of a single rail, and they are notched on the under side, at a, to receive one end of the wire loop p, which is larger at top than at the bottom. This loop p is hooked over a projection, o', in the notch in the first rail A and brought up over the two rail ends. Then the end of the brace G is inserted in the loop until its shoulder g rests on the top of the two rails, and as the lower end is borne down, acting as a lever, it binds the ends of the rails firmly together, and, by inserting the pin n in one or other of the openings l or m in the sill I, the rail ends and brace are secured.

In Fig. 1 is shown the panel adjusted for level ground, the upright B' resting on a common sill, the hole for the pin to pass through B' and rail A, and the upright B resting on the sill I and connected therewith by the pins F and k, and supported by the brace G, the latter having its pin n in the upper hole, l, of the sill.

On a side hill the level of the panel will be changed by removing pin n to hole l' or l'', according to the pitch of the hill, and where the ground is ascending in line of the fence as well as sideling laterally, the brace end will be placed in the bevel on the opposite side of the sill and the pin n inserted in m or m', according to the pitch, while at the same time the pin will be removed from the opening D in the upright B' to a similar opening in the upright B, passing also through the rail A, the panel being partly folded for the purpose.

The sill I may be partly embedded in the earth, in which case the sill I', under the upright B', may be dispensed with, and the latter sill may be dispensed with in all cases without affecting the working of my device, by making the upright B' slightly longer than upright B.

The corner connection of two panels at right angles is made by means of two dowel-pins, one of which, r, passes through rail A into rail A', and the other, s, at right angles, passes through the rail of the second panel and enters an opening in the upright B' of the first panel.

No base is needed nor used at a corner. The several pins are all easily removable, making the panels detachable at will, and portable.

I do not design to limit myself to the number of openings l or m shown in the sill, nor to the position of the openings in the uprights B and B' through which the pin passes into the rail A. Also, I desire to strengthen the rail by a rib on its back, if such strengthening becomes necessary, to prevent sagging or bending in case of using a very long rail.

Having thus described my invention, what I claim as new, and desire to secure by Letters Patent, is—

1. A folding fence-panel consisting of two single uprights, B and B', pivotally attached to the rail A, (said uprights and said rail being of the same width,) and a series of three or more slats or wires extending from B to B' and attached thereto by the projections b, each pair of said projections being placed slightly to one side of the pair below, whereby when the panel is folded for transportation it occupies a space equal only to the width of the rail A, substantially as described.

2. In a fence-panel, the combination of the rail A, the uprights B B', the series of wires or slats C, the sills I I', and the brace G, provided with the shoulder g and the pin-connection n o for the sill, all substantially as described.

3. The combination of the two rails A A' of adjacent panels, rabbeted and notched, as described, with the brace G, the sill I, and the wire-loop p, said brace and loop serving the double purpose of support and acting as a lever to bind the ends of the rails together for the purpose of connecting two panels in a straight line, all as shown and described.

4. The combination of the two rails A A' with the upright B', and the pins r and s, for the purpose of making a connection of two panels placed at right angles to each other, all as hereinbefore described.

5. The combination of the uprights B and B', having projections b, with the series of slats or wires C, the rail A, the sill I, having plate j, notch i, and projection F, the brace G, having shoulder g, and the loop p, all constructed and operating substantially as hereinbefore shown and described.

In testimony whereof I affix my signature in presence of two witnesses.

JAMES J. OGILVIE.
